(57) CLAIM

The ornamental design for a nightstand, as shown and described.

DESCRIPTION

FIG. 1 is a top, right, front perspective view of a nightstand showing our new design;

FIG. 2 is a top, left, front perspective view thereof;

FIG. 3 is a bottom, rear perspective view thereof;

FIG. 4 is a front view thereof;

FIG. 5 is a rear view thereof;

FIG. 6 is a right side view thereof;

FIG. 7 is a left side thereof;

FIG. 8 is a top view thereof; and,
FIG. 9 is a bottom view thereof.

The broken lines illustrate portions of the nightstand that form no part of the claimed design.

1 Claim, 9 Drawing Sheets
